UNITED STATES PATENT OFFICE.

JOSEPH POLITE, OF DETROIT, MICHIGAN.

DESIGN FOR A MEMORANDUM HOLDER FOR AUTOMOBILE STEERING WHEELS.

Application filed October 19, 1925. Serial No. 15,168. Term of patent 14 years.

To all whom it may concern:

Be it known that I, JOSEPH POLITE, a subject of the King of Italy, residing at Detroit, in the county of Wayne and State of Michigan, have invented a new, original, and ornamental Design for a Memorandum Holder for Automobile Steering Wheels, of which the following is a specification, reference being had to the accompanying drawing, forming part thereof.

Figure 1 is a plan of the memorandum holder for automobile steering wheels, showing my new design, and

Fig. 2 is an edge view of the same.

I claim:

The ornamental design for a memorandum holder for automobile steering wheels, as shown.

JOSEPH POLITE.
